UNITED STATES PATENT OFFICE

144,634

DESIGN FOR KNITTED LACE FABRIC

Samuel Saftlas, Newark, N. J.

Application July 28, 1945, Serial No. 121,035

Term of patent 7 years

(Cl. D47—6)

To all whom it may concern:

Be it known that I, Samuel Saftlas, a citizen of the United States residing at Newark, in the county of Essex and State of New Jersey, have invented a new, original, and ornamental Design for Knitted Lace Fabric, of which the following is a specification, reference being had to the accompanying drawing, forming a part thereof.

Referring to the drawing:

The figure is a view of a knitted lace fabric embodying my new design.

I claim:

The ornamental design for knitted lace fabric, as shown.

SAMUEL SAFTLAS.
